UNITED STATES PATENT OFFICE.

WILLIAM F. EDWARDS, OF WARREN, OHIO.

METALLIC ROOF.

1,426,558.

Specification of Letters Patent. Patented Aug. 22, 1922.

Application filed August 11, 1921. Serial No. 491,545.

To all whom it may concern:

Be it known that I, WILLIAM F. EDWARDS, a citizen of the United States, residing at Warren, in the county of Trumbull and State of Ohio, have invented a new and useful Metallic Roof, of which the following is a specification.

This invention aims to provide a roof, the constituent members of which may be welded readily, to prevent leakage. Another object of the invention is to provide a roof-forming element so constructed that the result above mentioned may be attained.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in plan, a portion of a blank out of which the roof-forming element is made; Figure 2 is a plan showing one end of the roof-forming element, complete; Figure 3 is an end elevation of the roof-forming element; Figure 4 is a perspective view showing how the roof-forming elements are joined; and Figure 5 is a longitudinal section taken through two connected roof-forming elements.

Each roof-forming element is fashioned from a metal plate 1 having slits 2 in its ends, the slits defining a tongue 3 at each end of the plate 1. Adjacent to its longitudinal edges 4, the plate 1 is bent along parallel lines 5, spaced from the slits 2, to form longitudinal flanges 6 disposed at right angles to the plate 1. The tongues 3 are bent to form transverse flanges 7, and to form projections 8 on the body 9 of the finished article, the projections 8 being located between the ends of the flanges 7, and the flanges 6.

In practical operation, the flanges 7 of two roof-forming elements are brought into abutment as shown in Figure 4, the flanges 6 being overlapped on each other and the projection 8 of one roof-forming element be-

ing overlapped on the body 9 of the other roof-forming element, as shown particularly in Figure 5. The parts 8 and 9 are welded together, the flanges 7 are welded together, and the flanges 6 are welded together where they overlap. It is to be observed that the ends of the flanges 7 are spaced as indicated at 10 in Figure 4 from 60 the overlapped portions of the flanges 6, to form passages, through which the water may run down the roof.

Considered as a roof, the device forming the subject matter of this application comprises body members 9 having transverse flanges 7 which are disposed in abutment, as shown in Figure 4, the body members having longitudinal flanges 6 which are overlapped on each other, the transverse flanges 70 7 being spaced inwardly from the ends of the body members 9, as indicated in Figure 2, to form projections 8, which are joined to the longitudinal flanges 6, the projections 8 being overlapped on each other. The ends 75 of the transverse flanges 7 are spaced, as shown at 10 in Figure 4, from the longitudinal flanges 6 to permit the aforesaid overlapping of the longitudinal flanges 6, and to permit the aforesaid overlapping of the projections 8 of the body members 9.

What is claimed is:—

A roof comprising body members having transverse flanges which are disposed in abutment, the body members having longitudinal flanges which are overlapped on each other, the transverse flanges being spaced inwardly from the ends of the body members to form projections which are joined to the longitudinal flanges and are 85 overlapped on each other, the ends of the transverse flanges being spaced from the longitudinal flanges to permit the aforesaid overlapping of the longitudinal flanges and to permit the aforesaid overlapping of the 90 projections of the body members.

In testimony that I claim the foregoing as my own, I have hereto affixed my signature in the presence of two witnesses.

WILLIAM F. EDWARDS.
